MANIFOLDING DEVICE

Filed Aug. 7, 1922

UNITED STATES PATENT OFFICE

ALBERT W. METZNER, OF DAYTON, OHIO, ASSIGNOR TO JOHN Q. SHERMAN, OF DAYTON, OHIO

MANIFOLDING DEVICE

Application filed August 7, 1922. Serial No. 580,375.

My invention relates to devices for use as a stylus which will form impressions of the desired notations on a series of superimposed webs of paper without the use of carbon paper or other interposed, impregnated material.

In its essential aspects my invention comprises a carrier and a pointed stylus, which is rapidly reciprocated, so that as the holder is moved along over a piece of paper, such as the top web of a pile to be manifolded, the stylus will penetrate all webs and leave a line of small holes outlined with ink in each web.

Such a device is valuable in all autographic manifolding work and has the advantage in addition of making a non-erasable impression.

Among my objects are the provision of a simple form of actuating mechanism, and a small and adequate holder which can be manipulated as a pen or pencil.

I accomplish my objects by that certain construction and arrangement of parts to be hereinafter more specifically pointed out and claimed.

In the drawings,

Figure 1 is an elevation of the device partly broken away to show the interior of the stylus holder.

Figure 2 is a side elevation of the device showing the paper contact member and the method of writing on paper.

Figure 3 shows a detail of the stylus oscillating shaft.

Figure 4 is a detail of the upper end of the stylus.

Figure 5 is a detail of the point of the stylus.

Figure 6 is a detail section showing the electrical connections.

Figure 7 is a perspective of the paper contact means.

The stylus holder is formed of a lower tubular portion 4 ending in a hollow point 5. At the upper end of this portion is a cylindrical portion 6 having a reduced member or sleeve portion 7 to insert within the portion 4. This sleeve or plug 7 has air holes 8 therein and also a central passageway for the stem 9 of the stylus 10.

The stylus extends out through a hole suitably packed in the tapered end 11 of the barrel 4. It is formed with grooves 12 for carrying ink, which grooves come down very closely to the apex of the stylus.

Within, the upper barrel portion 6 of the stem of the stylus is equipped with a disk 13 serving as a piston and the lower barrel is used as a reservoir for ink. As will be noted the operation of the stylus will result in a forced feed of ink to the inking grooves 12.

I provide a motor 14 having a speed control switch 15 and having a flexible shaft 16 connected to the motor. This shaft 16 is carried in the usual casing 17 and enters the removable cap 18 at the end of the upper barrel 6.

Within the barrel portion 6 is mounted a pinion 19 to the arbor of which the flexible shaft is connected. The pinion 19 is beveled and meshes with another beveled pinion 20, said pinion being on an arbor 21 held transversely of the barrel.

The arbor 21 has a small cam 22 thereon, and at the upper end of the stylus stem is mounted a strap or ring member 23 for engaging over the cam, and pivoted to the stem.

As the arbor revolves with the cam 22, the stylus stem is caused to reciprocate, thereby reciprocating the stylus.

The tapered end of the ink barrel has mounted on it a small thimble 24, to which is hinged, by means of a screw 25, a supporting foot 10^a for the pen. By adjusting the foot and tightening the screw, the desired angle for any writer can be arrived at. The foot is forked so as to extend along both sides of the apex of the barrel, and the stylus reciprocates between the tines of this foot.

In writing, the operator permits the foot to bear on the paper and sets in motion the stylus operating device. The arrangements are such that in its upper position the stylus point comes above the base of the foot, so that with a proper speed to the reciprocation, as determined by the writer's speed, the pen may be moved over paper in the usual manner of writing. The ink within the barrel will be picked up in the grooves of the stylus and the piston on the stylus will force

air into the ink barrel and cause a regulated flow proportional to the speed of stylus reciprocation. The piston chamber is not absolutely air tight, but the escape of ink with the stylus will be easier than escape of air above the piston. Hence the rapid moving piston will tend to force tiny quantities of ink toward the stylus end of the barrel and suck in replacing air about the joints.

10 As a convenient method of starting and stopping the operating parts of the pen I extend the wires 26 and 27 of the motor circuit so that a device on the pen serves as the switch for starting and stopping.

15 I show, as one form of device, the wire extending into the removable cap on the top of the pen, where by means of screws 28, the wires are connected to conductor strips 29 and 30, set into the sides of the cap and preferably coated over with hard rubber.

20 As the barrels and caps will be made of insulating material such as rubber, in the example shown, no further insulation of the strips is necessary. The barrel portion 6 has like strips 31, 32, and the barrel portion 4 has like strips 33, 34. In the base of the top cap are contact pieces 35, which, when the cap is screwed down tight, will engage with the strips 31 and 32.

30 Also in the base of the beaded portion or shoulder 6^a on the barrel are contact pieces 36 which will engage with the strips 33 and 34.

35 The various strips are set in channels in the rubber and covered with a rubber coating and near the tapered portion of the pen the strip 34 is brought around the barrel in a groove and terminates in a contact plug 37.

40 A spring finger 38 is screwed down to the barrel with a screw which engages in the strip 33, so that depression of the finger will accomplish an electric contact between the strips 33 and 34.

45 It is evident that the user will press in on the finger or button 38 when he desires to write, and that the stylus will penetrate within the limits of its motion as many webs of paper as are piled up for purposes of receiving impressions.

50 Such a pile of paper, as at 39, may be mounted on the writing table 40 of an autographic register and the use of the pen will cause lines of closely arranged dots to appear in all webs that are penetrated, each dot being surrounded by an inked wall.

55 For signing checks and making duplicate or plural copies of entries on blank forms, my device is very valuable.

Having thus described my invention, what I claim as new and desire to secure by Letters Patent, is:—

60 1. A device of the character described, comprising an ink barrel, a stem therein, said stem having a stylus to project beyond the 65 stem, an ink forcing piston on the stem

adapted to force an ink supply to the stylus and means for reciprocating said stem.

70 2. A device of the character described, comprising an ink barrel, a stem therein, said stem having a stylus to project beyond the stem, an ink forcing piston on the stem adapted to force an ink supply to the stylus, means for reciprocating said stem, and a rest on the barrel to engage paper on which impressions are to be made.

75 3. A device of the character described, comprising a holder having a paper contact means, and a paper penetrating pointed member adapted to reciprocate in the holder to bring its point above and below the level of the paper contact means, said contact means having a pivoted foot to permit the holder to slant at the desired angle when writing.

ALBERT W. METZNER.
